UNITED STATES PATENT OFFICE.

WILLIAM BURNETT, OF BOSTON, MASSACHUSETTS, ASSIGNOR TO ROBERT BURNETT, OF NEW YORK, N. Y.

PRESSURE-GAGE.

Specification of Letters Patent No. 33,062, dated August 13, 1861.

To all whom it may concern:

Be it known that I, WILLIAM BURNETT, of Boston, in the county of Suffolk, in the State of Massachusetts, have invented certain Improvements in Pressure Gages or Indicators; and I do hereby declare that the following is a full and exact description thereof, reference being had to the accompanying drawings, and to letters of reference marked 10 thereon, the same letters referring to like parts where shown in both figures.

The nature of my invention consists in a novel mode of introducing the pressure into the cavity behind the elastic plate, in gages 15 in which such means are employed to obtain a first motion; and further consists in a novel arrangement of mechanism by which the first motion in pressure gages may be transmitted to the index hand or pointer.

20 To enable others skilled in the art to make and use my invention, I will proceed to describe its construction and operation, reference being had to the accompanying drawings, making part of this specification.

25 A circular metallic case (A) of proper depth to receive the working parts, is provided with a back of sufficient thickness to resist without injury, any pressure to which the gage may be subjected. In this latter is 30 provided a cavity (B) of suitable depth and diameter, which, when covered by the elastic plate (C), forms the chamber into which the pressure to be measured is introduced. The elastic plate (C) is secured in its place by

35 means of a metallic ring (D) of proper dimensions, which is held firmly down on the top of the plate by means of screws (E) which pass through the metallic ring (D), and elastic plate (C), and are screwed into

40 the back of the case. One end of a rigid bar or arm (F) is firmly bolted to the elastic plate (C) at a point considerably removed from its center, as shown in the drawing, and at that part of its surface which assumes, when pressure is admitted beneath the plate, the steepest angle when considered relatively to the plane represented by the surface of the plate when in a state of rest or equilibrium. From a short standard 45 (G), which is either cast upon or screwed into the metallic ring (D), is suspended, by means of a properly fitted pin, a vibrating

50 bar (H), which is connected by a link (J)

to the free end of the rigid arm (F), before described.

In fitting the vibrating bar (H) into the standard (G), a little side oscillation is permitted to the lower end of the vibrating bar, to give freedom to its action against a spiral shaft (L), which carries upon its outer end 55 the index hand or pointer (M). A flange projection (K) of nearly triangular form, is cast upon the metallic ring (D), and forms a bearing or step for the inner end of the spiral shaft (L). This projecting flange 60 (K) is sufficiently far removed from the elastic plate (C) to allow of the free working of the latter when subjected to pressure.

A bracket (N), which is secured to the projecting flange (K) by screws (o), furnishes 65 a bearing for the outer end of the spiral shaft. Cast upon the metallic ring (D) are three projections (P) to which is secured, by screws (p), the index plate (Q). A screw ring (R) holds in its place the circular glass 70 plate (S) which protects the internal mechanism from dust or injury. Upon the metallic ring (D) is also cast a suitable enlargement or boss (T), to increase its thickness at 75 this particular place for the purpose of having sufficient material into which may be screwed the pipe (U), through which the pressure is introduced. A hole sufficiently large to receive the pipe (U), is drilled into the edge of the ring at this place, and another hole (V) of smaller diameter, is then 80 drilled into the back of the ring, so as to intersect the first; the plate (C) is provided with an opening through it, in continuation of this passage (V), which communicates, by 85 means of a groove or channel (X) below the elastic plate, with the pressure chamber (B). By this arrangement for introducing the pressure, I am enabled to employ an elastic plate the full size of the interior of the case, 90 and at the same time to secure a flush back to the gage, rendering it easy of attachment to any flat surface, and avoiding the unsightly and inconvenient projections on the back of the case, which would be otherwise 95 necessary for the introduction of the pressure, where so large an elastic plate is employed.

The seat upon which the elastic plate rests is provided with a suitable packing to prevent leakage, and a thin packing is also in-

roduced between the ring (D) and the elastic plate, at that point where the pressure is introduced through the elastic plate into the channel (X) leading into the pressure chamber. The metallic ring (D) may be cast as a flange on the inside of the case (A), and form the seat for the elastic plate, which, in that case, would be inserted from behind, the thick portion of the back of the case (A) being made in a separate piece for this purpose; the pressure, however, would still be introduced into the ring (D) in front of the elastic plate, thence through the plate itself, into the channel behind the plate, 15 communicating with the pressure chamber. But I prefer the arrangement of making the ring (D) separate from the case, as represented.

One side of the enlarged central portion 20 of the shaft (L), between its bearings, is cut spirally, nearly throughout its whole length, by filing or other means, and when finished, would present, approximately, a semi-cylindrical cross section. The spiral surface thus 25 formed, I make of a diminishing pitch, that is to say, of a coarser pitch at the end of the shaft nearest the elastic plate, diminishing the same toward the outer end of the shaft in the same ratio in which motion is com- 30 municated to the vibrating bar (H), through the action of the pressure, from minimum to maximum, on the elastic plate. The object of this is to secure uniform divisions on the index plate for equal increments of pressure, 35 which would not result unless some such expedient were adopted.

Used as a vacuum gage, the vibrating bar (H) would commence its motion from the outer end of the shaft, as the movement of 40 the elastic plate would be, in this case, reversed, and the spiral shaft must also be reversed so that the coarser pitch is at the outer end, the same diminishing as it approaches the end nearest the elastic plate, 45 for the same reasons stated above. The spiral shaft (L) has another important peculiarity of form, which arises from the fact that the spiral surface has been formed with direct reference to the point of suspen- 50 sion of the vibrating bar (H), with the view of securing between the working face of the vibrating bar and the spiral face of the shaft, a proper fit and contact throughout the entire movement; which would not be the 55 case unless the various angles assumed by the vibrating bar throughout its motion were thus accommodated. Thus, a shaft of similar transverse section to that described, the spiral surface of which had not been formed 60 with reference to the point of suspension of a bar by which it was to be driven, although such vibrating bar might be fitted properly to its spiral surface at the center of the shaft, it would not fit equally well at the 65 ends. At one end, on account of the vibrat-

ing bar having assumed an angle more co-incident with the direction of the spiral, it would be quite loose, permitting uncontrolled motion of the index pointer, within certain limits: At the other end, the vibrating bar 70 having in this case assumed an angle less co-incident with the direction of the spiral, it would be forced out of proper contact.

The end of the vibrating bar which works against the spiral surface of the shaft, is 75 rounded on the working face, and this end of the bar, as well as the shaft itself, both of which are made of steel, is hardened by tempering. The bracket (N) which supports the outer end of the spiral shaft, is placed so 80 near to the back of the vibrating bar (H), that, although sufficient clearance is allowed for free action, it cannot in any case, recede so far from its proper contact with the spiral surface, as to permit indications very ma- 85 terially differing from the true pressure. But in addition to having provided this safe- 90 guard, the vibrating arm (H) is furnished with a light flat spring (Y), one end of which is securely united to it, at a proper distance above its point of contact with the shaft, the other end reaching down to the end of the vibrating bar, and embracing the shaft in such a manner as to draw the vibrat- 95 ing bar nicely and delicately into its proper seat and contact with the spiral surface of the shaft. This spring (Y) may be attached to the back of the bar (H), its lower end bearing against the bracket (N), but I prefer the application represented in 100 the drawing. I sometimes apply a light spi- 105 ral spring (Z), stretched between the vibrat- ing bar (H) and the rigid arm (F), for the purpose of taking up any slack in the pivots, which may result from wear.

The operation of the gage is as follows: The pressure is admitted into the chamber (B) behind the elastic plate (C), by means of a pipe (U) and passages (V X) as represented. The elastic plate, bearing the rigid 110 arms (F), is bulged outward, throwing the top of the arm forward. This latter move- 115 ment is communicated by means of the link (J) attached, to the vibrating bar (H), the lower end of which being engaged in the spiral shaft (L) causes it to revolve, and indicate the pressure, by means of the pointer (M) carried on its outer end, and working over the index plate.

I do not claim to have invented elastic 120 metallic plates to be used in pressure gages, for the purpose of deriving motion there- 125 from upon the application of pressure, as I am aware they are now used, and well known. Neither do I here claim the mode described of obtaining an enlarged first motion, through the agency of an arm affixed to the elastic plate at a point removed from its center, as this is the subject of a patent now about to issue to Robert Burnett, as my 130

assignee. Neither do I claim broadly the use of spiral or screw shafts in pressure gages, to give motion to an index hand or pointer, as I am aware they have been used 5 of various forms.

What I claim as my invention, and desire to secure by Letters Patent, is—

1. The mode herein described, of admitting the pressure into the chamber behind 10 the elastic plate, viz:—by first introducing the pressure into the ring in front of the elastic plate, thence through the plate itself, into a channel communicating with the pressure chamber, substantially in the manner 15 and for the purpose herein specified.

2. The use of a spiral shaft, to give motion to a pointer, when the same is constructed by cutting away spirally, one half, 20 of the material of the shaft, so as to present, approximately, in its transverse section, a 25 semi-cylindrical body, substantially as herein described, by which I am enabled to secure a working face equal to the whole diameter of the shaft, while sufficient stiffness is retained to present no obstacle to its manufacture, and to insure permanency of character.

3. Operating the spiral shaft, giving motion to a pointer, by means of a vibrating bar which is forced into proper contact with

the spiral surface, by a spring attached to 30 the bar and operating transversely to the axis of the shaft, substantially as described.

4. Providing a guard to prevent the vibrating bar, which operates the spiral shaft, from receding so far from its proper contact 35 with the spiral surface as to permit indications very materially differing from the true pressure,—by placing an unyielding body near to the back of the vibrating arm, and parallel to the axis of the shaft, substan- 40 tially as described.

5. A screw or spiral shaft of diminishing pitch, to give motion to a pointer, substantially as herein described.

6. Forming the spiral surface of a shaft, 45 employed to give motion to a pointer, with a reference to the point of suspension of a vibrating bar working in contact with said spiral surface,—by which arrangement of the two I secure a proper working contact 50 throughout the length of the shaft, and in all positions which are assumed by the vibrating bar, substantially in the manner and for the purpose herein specified.

WM. BURNETT.
